Primary Examiner — Deanna L Pratt*Assistant Examiner* — Natasha Vujcic(74) *Attorney, Agent, or Firm* — Heslin Rothenberg Farley & Mesiti P.C.(57) **CLAIM**

The ornamental design for a lighting fixture, as shown and described.

DESCRIPTION

FIG. 1 is a perspective view of a lighting fixture in accordance with the new design;

FIG. 2 is a front elevational view thereof;

FIG. 3 is a right side elevational view thereof;

FIG. 4 is a left side elevational view thereof; and,

FIG. 5 is a bottom view thereof.

The broken lines in the drawings illustrate portions of the lighting fixture which form no part of the claimed design.
